Primary Examiner — Kevin K Rudzinski*Assistant Examiner* — Paul D Bohannon(74) *Attorney, Agent, or Firm* — JCIP Global Inc.(57) **CLAIM**

The ornamental design for a massage chair, as shown and described.

DESCRIPTION

FIG. 1 is a perspective view of a massage chair showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is another perspective view thereof with a pillow placed thereon.

The heavy broken line showing of stitch lines in FIGS. 1-7 forms portions of the claimed design, while the light broken line portions of the massage chair in FIGS. 1-7 represent portions of the massage chair that form no part of the claimed design.
